(57) **CLAIM**

The ornamental design for a bayonet mount, as shown and described.

DESCRIPTION

FIG. 1 is an isometric view of a bayonet mount in accordance with the present disclosure;

FIG. 2 is another isometric view of the bayonet mount of FIG. 1;

FIG. 3 is a right side elevation view of the bayonet mount of FIG. 1;

FIG. 4 is a left side elevation view of the bayonet mount of FIG. 1;

FIG. 5 is a rear elevation view of the bayonet mount of FIG. 1;

FIG. 6 is a front elevation view of the bayonet mount of FIG. 1;

(Continued)

FIG. 7 is a top view of the bayonet mount of FIG. 1; and, FIG. 8 is a bottom view of the bayonet mount of FIG. 1. The broken lines in the Figures are directed to environment and form no part of the claimed design.

1 Claim, 5 Drawing Sheets
